REFRIGERATOR CABINET

William C. Mason, Jefferson County, Ky., assignor to General Electric Company

Filed Dec. 10, 1969, Ser. No. 20,428

Term of patent 7 years

Int. Cl. D15—11

U.S. Cl. D67—3

The figure is a front perspective view of a refrigerator cabinet embodying my new design;

The side not shown is the same as the side shown and the rear is plain and unornamented.

I claim:

The ornamental design for a refrigerator cabinet, substantially as shown and described.
